UNITED STATES PATENT OFFICE.

JAMES MUNTON, OF MAYWOOD, ILLINOIS, ASSIGNOR TO LATROBE STEEL AND COUPLER COMPANY, OF PHILADELPHIA, PENNSYLVANIA, A CORPORATION OF NEW JERSEY.

COUPLING FOR LOCOMOTIVE-ENGINES AND TENDERS.

No. 806,824.

Specification of Letters Patent.

Patented Dec. 12, 1905.

Application filed October 18, 1905. Serial No. 282,535.

To all whom it may concern:

Be it known that I, JAMES MUNTON, a citizen of the United States, residing in Maywood, in the county of Cook and State of Illinois, 5 have invented a new and useful Improvement in Couplers for Locomotive Engines and Tenders, of which the following is a specification.

My invention relates to improvements in 10 couplers for locomotive engines and tenders.

The object of my invention is to provide a locomotive engine or tender coupler of a simple, efficient, and durable construction and adapted to permit the necessary lateral or 15 swinging movement of the coupler and in which the coupler may be readily adjusted to the proper height above the rails as the locomotive-tires wear away or the springs weaken, which may be quickly and easily removed and 20 replaced, and which at the same time will be very securely and strongly anchored in place.

My invention consists in the means I employ to practically accomplish this object or result—that is to say, it consists in a coupler, preferably of the ordinary Master Car-Builders' type, provided with an integral shank furnished with a rounded or partially cylindrical pivot-head having convex, concave, or curved upper 25 and lower faces in connection with a socket-piece secured to or forming part of the locomotive or tender frame and provided with a partially round or cylindrical socket having a curved lower or bottom face and receiving and fitting said pivot-head of the coupler— 30 shank and furnished with angle stops or shoulders adapted to engage the shank of the coupler to limit the lateral or swinging movement of the coupler and a removable cap-plate having a curved lower face fitting the curved upper 35 face of the pivot-head of the coupler and secured to said socket-piece, and one or more removable filler-plates, each having curved or dished upper and lower faces corresponding to the curved upper and lower faces of the 40 pivot-head of the coupler and of the bottom face of the socket-piece, one or more of which filler-plates may be placed above or below the pivot-head of the coupler, according as the 45 condition of the tires and springs may require, 50 to bring the coupler to the proper level.

My invention also consists in the novel construction of parts and devices and in the novel

combinations of parts and devices herein shown or described.

In the accompanying drawings, forming a 55 part of this specification, Figure 1 is a plan view of a locomotive or tender coupler embodying my invention. Fig. 2 is a vertical longitudinal section on the line 2 2 of Fig. 1. Fig. 3 is a cross-section on line 3 3 of Fig. 60 1, and Fig. 4 is a detail plan view of one of the removable filler-plates.

In the drawings, A represents a coupler of the Master Car-Builders' type having the customary forked draw-head *a* and pivoted 65 knuckle *a'*. The coupler A has an integral shank B, furnished with an integral rounded or partially-cylindrical pivot-head B'. The pivot-head B' has a conical or curved bottom face *b*, the same being preferably convex, and 70 a similarly curved or concave top face *b'*. The pivot-head B' also has, preferably, a central opening *b*², so that when the outer periphery of the rounded or cylindrical pivot-head becomes worn by use or the socket in which it 75 fits becomes worn the head may be swaged out after being heated and thus enlarged, so that it will again properly fit its surrounding socket.

D is a socket-piece having an upright flange 80 *d* and horizontal flange *d'* for attachment to the front sill or framework of the locomotive or tender. This socket-piece D, which is preferably of cast metal, is furnished with a partially-cylindrical socket D', having a curved 85 or non-flat bottom face *d*², adapted to receive and fit the cylindrical pivot-head B' of the coupler. The socket-piece D is further provided with angle shoulders or flanges *d*³, which serve as stops to limit the lateral or swinging 90 movement of the coupler from side to side as the train passes around curves. The socket-piece D is further provided, just back of its socket D', with a slot or recess *d*⁴ to receive the holding-lugs *f*' at the rear edge of the 95 cap-plate F, which fits on top of the rim *d*⁵ of the socket D' and is removably secured thereto by bolts *d*⁶, which extend through ears or lugs *d*⁷ on the socket-piece. The removable cap-plate F has a curved or conical lower face 100 *f*, the same being preferably convex and corresponding to the curved top face *b'* of the pivot-head B' of the coupler.

G G are removable curved or dished filler-

plates, corresponding in form to the socket D' in the socket-piece D and their curvature corresponding to and fitting the curved faces b b' of the pivot-head B' and the curved bottom face d² of the socket D' in the socket-piece D.

By reason of the curvature or dish shape of the top and bottom faces b b' of the pivot-head and of the bottom face d² of the socket 10 D' and of the under face f of the cap-piece F in connection with the curved or dished 15 filler-plates G the pivot-head B' of the coupler is very securely anchored or held in the socket-piece, while permitted to turn or swing 20 freely from side to side. By placing one or more of the curved or dished removable filler-plates G above or below the coupler, as may be required, the coupler may be adjusted to 25 the proper level or height, and thus compensate for the wear of the locomotive-tires or the sagging of the springs or other causes tending to vary the height of the coupler. When the pivot-head B' or its socket D' becomes so worn that there is too much play, the 30 pivot-head B' may be enlarged by simply heating the same and swaging it out to a larger external diameter.

My invention is an improvement upon the locomotive or tender coupler shown and described in application, Serial No. 233,638, of 35 John H. Lewis and Louis G. Kunzer, filed November 21, 1904, and I do not claim the invention forming the subject of said application. In the coupler of said Lewis and 40 Kunzer application the pivot-head of the coupler has flat upper and lower faces and the socket-piece and cap-piece have corresponding flat meeting faces, and consequently the upper and lower faces of the pivot-head do 45 not have any anchoring or holding function. In my improvement the upper and lower faces of the pivot-head of the coupler and the corresponding meeting faces of the socket-piece and cap-piece exert an anchoring or holding function by reason of their curved, dished, or 50 non-flat shape in respect to each other.

To increase the holding function of the removable cap-plate F, I provide the same with one or more shoulders or lugs f', which engage 55 the socket-piece D, the socket-piece being preferably provided with notches d⁸ to receive the holding lugs or projections f' of the cap-piece.

I claim—

55 1. A coupler for locomotives or tenders having a shank furnished with an integral cylindrical pivot-head having curved or non-flat upper and lower faces in combination with a socket-piece furnished with a cylindrical 60 socket having a curved or non-flat bottom face, and receiving and fitting said pivot-head of the coupler, and a cap-plate removably secured to said socket-piece above the pivot-head of the coupler and having a curved or 65 non-flat lower face corresponding to the curved

or non-flat upper face of the pivot-head of the coupler, substantially as specified.

2. A coupler for locomotives or tenders having a shank furnished with an integral cylindrical pivot-head having curved or non-flat upper and lower faces in combination with a socket-piece furnished with a cylindrical socket having a curved or non-flat bottom face, and receiving and fitting said pivot-head of the coupler, and a cap-plate removably secured to said socket-piece above the pivot-head of the coupler and having a curved or non-flat lower face corresponding to the curved or non-flat upper face of the pivot-head of the coupler, and a removable curved or non-flat 75 filler-plate fitting in the socket of the socket-piece to adjust the height of the coupler, substantially as specified.

3. A coupler for locomotives or tenders having a shank furnished with an integral cylindrical pivot-head having curved or non-flat upper and lower faces in combination with a socket-piece furnished with a cylindrical socket having a curved or non-flat bottom face and receiving and fitting said pivot-head of the coupler, and a cap-plate removably secured to said socket-piece above the pivot-head of the coupler and having a curved or non-flat lower face corresponding to the curved or non-flat upper face of the pivot-head of the coupler and a plurality of removable curved or non-flat filler-plates fitting in the socket of the socket-piece to adjust the height of the coupler, substantially as specified.

4. A coupler for locomotives or tenders having a shank furnished with an integral cylindrical pivot-head having a curved or non-flat lower face in combination with a socket-piece furnished with a cylindrical socket, having a curved or non-flat bottom face receiving and fitting said pivot-head of the coupler and provided with shoulders or stops to limit the lateral or swinging movement of the coupler, and a cap-plate removably secured to said socket-piece above the pivot-head of the coupler, substantially as specified.

5. A coupler for locomotives or tenders having a shank furnished with an integral cylindrical pivot-head, having a curved or non-flat upper face, in combination with a socket-piece 115 having a cylindrical socket receiving and fitting said pivot-head of the coupler, and a cap-plate removably secured to said socket-piece above the pivot-head of the coupler, and having a curved or non-flat face corresponding to the curved or non-flat upper face of the pivot-head of the coupler, substantially as specified.

6. A coupler for locomotives or tenders having a shank furnished with an integral cylindrical pivot-head having curved or non-flat upper and lower faces in combination with a socket-piece furnished with a cylindrical socket having a curved or non-flat bottom face, and receiving and fitting said pivot-head of the coupler, and a cap-plate removably secured to 125 130

said socket-piece above the pivot-head of the coupler and having a curved or non-flat lower face corresponding to the curved or non-flat upper face of the pivot-head of the coupler, 5 said removable cap-plate having a holding shoulder or lug engaging said socket-piece, substantially as specified.

7. A coupler for locomotives or tenders having a shank furnished with an integral cylindrical pivot-head having curved or non-flat upper and lower faces in combination with a socket-piece furnished with a cylindrical socket having a curved or non-flat bottom face and receiving and fitting said pivot-head 10 of the coupler, and a cap-plate removably secured to said socket-piece above the pivot-head of the coupler and having a curved or non-flat lower face corresponding to the curved or non-flat upper face of the pivot-head of the 15 coupler and a plurality of removable curved or non-flat filler-plates fitting in the socket of the socket-piece to adjust the height of the coupler, said removable cap-plate having a holding shoulder or lug engaging said socket-piece, 20 substantially as specified.

8. A coupler for locomotives or tenders having a shank furnished with an integral cylindrical pivot-head having a curved or not-flat 25

lower face in combination with a socket-piece furnished with a cylindrical socket, having a curved or non-flat bottom face receiving and fitting said pivot-head of the coupler and provided with shoulders or stops to limit the lateral or swinging movement of the coupler, and a cap-plate removably secured to said socket-piece above the pivot-head of the coupler, 30 said removable cap-plate having a holding shoulder or lug engaging said socket-piece, substantially as specified.

9. A coupler for locomotives or tenders having a shank furnished with an integral cylindrical pivot-head, in combination with a socket-piece having a cylindrical socket receiving and fitting said pivot-head of the coupler, and a cap-plate removably secured 40 to said socket-piece above the pivot-head of the coupler, and having a curved or non-flat face corresponding to the curved or non-flat upper face of the pivot-head of the coupler, 45 said removable cap-plate having a holding shoulder or lug engaging said socket-piece, substantially as specified.

JAMES MUNTON.
